SAFETY STOP FOR INTERNAL COMBUSTION ENGINES

Ray E. Kittredge, Oil City, Pa., assignor to
Joseph Reid Gas Engine Company, Oil City,
Pa.Application October 22, 1934, Serial No. 749,445
Renewed March 10, 1938

3 Claims. (Cl. 123—198)

This invention relates to safety devices for internal combustion engines. The principal object of the invention is to provide a device which will stop the engine when it becomes overheated, due to lack of water or oil, or any other cause.

It is a special object of the invention to provide a device of this kind which is independent of external influences and consequently ready for the emergency at all times.

10 Electrical safety stops are known, but these have the disadvantage of being dependent upon a source of electricity which may fail at the critical moment, on account of a dead battery or breakage of lines in a storm. The present invention operates by direct mechanical means to cut off the supply of fuel when the engine becomes overheated.

An incidental object of the invention is to combine a fuel heating chamber with the safety stop.

By way of example, two forms of the invention are shown in the accompanying drawings, applied to a Diesel engine.

In the drawings,

25 Fig. 1 is a plan view of one form of safety stop in accordance with the invention.

Fig. 2 is a vertical section on the line 2—2 of Fig. 1.

30 Fig. 3 is a vertical section on the line 3—3 of Fig. 1.

Fig. 4 is a plan view of another embodiment of the invention.

35 Fig. 5 is a sectional view on the line 5—5 of Fig. 4, and

Fig. 6 is an elevation partly in section of the device shown in Fig. 5, the view being from the right.

The safety stop device illustrated in Figs. 1—3 is a unit adapted to fit into a hole 2 in the water jacket 4 of a Diesel engine. The unit comprises a lower plate 6 and an upper plate 8 held together by screws 10. The lower plate is fixed to the water jacket 4 by screws 12 and is formed with a chamber 14 capped by the upper plate 8 and adapted to receive fuel from an inlet 16. The fuel circulates from the inlet around a central column 18 to an opening 20 leading into a valve chamber 22 from which leads off an outlet port 24. The plate 6 being in direct contact with the water in the water jacket transmits heat from the water to the fuel passing through the channel 14, whereby the fuel is warmed and thus prepared for more rapid and complete volatilization.

At the top of the opening 20 is a valve seat 26 upon which seats a valve 28. This is the valve

which cuts off the fuel supply when the engine becomes overheated. It is normally pressed toward its seat by a spring 30, but is held in retracted position by a locking arm 32 engaging in a recess 34 in the shaft 36 of the valve. The locking arm 32 is pivoted on a screw 38 and is urged by a spring 40 into engagement with the valve shaft 36. A second arm 42 rigid with the locking arm 32 lies against a spool 44 threadedly mounted upon the upper end of a rod 46. The rod 46 is vertically slidable in a bush 48, which extends through a hole 50 in the upper plate 8 and screws into a threaded hole 52 in the central column 18 of the lower plate 6. The lower end of rod 46 bears a socket head 54 threadedly connected to end plate 56 of a thermostat bellows 58. The central bore of socket head 54 serves to guide the head upon a pin 59 standing up from the base of a cap 60 covering the thermostat bellows. The cap 60 is fixed to the plate 6 by 20 screws 62. This is a well known form of thermostat and need not be described in greater detail here. A rise in temperature causes the bellows to contract and raise the rod 46. At the lower end of spool 44 is an inclined skirt 64 which engages the arm 42 when the temperature in the water jacket space becomes sufficiently high to raise the spool 34 to that point. A further rise of the spool 34 cams the two armed lever 42, 32 in clockwise direction (Fig. 1) until it finally releases valve shaft 36, whereupon the valve is driven against its seat by spring 30 and closes the fuel line. A thermometer 41 may be mounted in the plate 6.

The height of spool 34 on rod 46 can be adjusted by unscrewing a lock nut 66, then screwing the spool up or down on the rod 46, and then tightening the lock nut 66 again. The height of the spool 34 on the rod 46 determines the degree of excessive temperature at which the valve stem 36 will be released.

It will be seen that the action of this safety stop is direct and positive and as nearly as possible free from external influences.

Valve 28 lies in a chamber 22 through which 45 the fuel passes on its way to the outlet; consequently, the valve stem must be packed to prevent the escape of fuel. As an ordinary packing might interfere with the correct seating of the valve, a bellows packing may be used, comprising 50 a bellows 70 tightly joined at its lower end to a plate 72 fixed in a slot 74 of the valve, and tightly joined at its upper end to a plate 76 held beneath a cap 78, which is fixed to the plate 8 by screws 80.

Figs. 4-6 show a safety stop device which is very similar to the one shown in Figs. 1-3. The similar parts bear the same reference characters as in the first three figures, with the addition of an "a". Lower plate 6a and upper plate 8a enclose a fuel heating space 14a from which a hole 20a leads into a valve chamber 22a. Controlling the hole 20a is a ball valve 84 above which is a valve stem 36a normally urged downward by a spring 30a. The spring bears at one end against a collar 86 resting on a shoulder 88 of the valve stem 36a and at its other end against a cap 90 screwed onto a threaded boss 92 on cap 78a in which the valve stem 36a is guided. At 15 the middle of the valve stem 36a is a recess 93 in which engages a ball 94 sliding in a hole 96 leading out through the side of cap 78a. A lever 98 fixed upon shaft 100 rockably mounted in bearings 102 has a finger 32a bearing against ball 94 and an oppositely directed arm 42a into which is screwed a set screw 104. The lower end of the set screw stands above a rod 46a connected to end plate 56a of a thermostat bellows 58a similar to the one shown in Fig. 1.

25 During the normal operation of the engine, the parts are substantially as shown in Fig. 5. In this position ball valve 84 is free to rise and let fuel pass through opening 20a. If the temperature in the water jacket space becomes excessive, 30 the thermostat bellows 58a forces up rod 46a, raises arm 42a, and lowers finger 32a sufficiently to allow ball 94 to slide outward in its hole 96. This frees valve stem 36a, which is forced down by spring 30a against ball valve 32a, thus shutting off the fuel. When the engine has cooled 35 sufficiently the device can be reset by pulling up knob 106 on the end of valve stem 36, whereupon arm 42a will drop down and press ball 94 back into recess 93, locking the valve stem 36a in retracted position.

In engines governed by by-passing fuel from the pressure side of the pump to the suction side the fuel entering the suction side in this way causes gassing and also variations in pressure which might be injurious to the suction line and to the packless joint at the valve. A vent 108 may be provided to relieve the variations in pressure and to provide an exit for the gas. This

vent may open to the atmosphere or to the top of the fuel storage tank.

Having described my invention, I claim:

1. In combination with the water jacket of an internal combustion engine, said water jacket 5 having an opening therein, a fuel control device comprising a chambered plate-shaped member adapted to fit over and close said opening, whereby its inner surface will be in direct contact with the water in said water jacket, fuel admission 10 and outlet means for said chamber, a valve controlling one of said means, means normally urging said valve to closed position, means for locking said valve open, a thermostat on the wall of said plate-shaped member in contact with the 15 water in said water jacket, and means controlled by said thermostat for releasing said locking means.

2. In combination with the water jacket of an internal combustion engine, said water jacket 20 having an opening therein, a fuel control device comprising a chambered plate-shaped member adapted to fit over and close said opening, whereby its inner surface will be in direct contact with the water in said water jacket, fuel admission 25 and outlet means for said chamber, a valve controlling one of said means, means normally urging said valve to closed position, means for locking said valve open, a thermostat on the wall of said plate-shaped member in contact with the 30 water in said water jacket, said thermostat being sealed to the bottom of said plate-shaped member to exclude water therefrom, said plate-shaped member having means forming a tubular channel therethrough, the inner end of which is covered 35 by said thermostat, and means connected to said thermostat and extending through said channel for releasing said locking means.

3. In a safety device for internal combustion engines, fuel supply means, a valve adapted to close said means, said valve having a recessed 40 stem for guiding the same in its movement, means normally urging said valve toward closing position, locking means engaging in the recess of said valve stem to hold said valve open, and means 45 for releasing said locking means, comprising a thermostat device mounted in the water jacket of the engine.

RAY E. KITTREDGE.
